UNITED STATES PATENT OFFICE.

ROBERT D. MCINTYRE, OF MANSFIELD, OHIO, ASSIGNOR OF ONE-HALF TO EDWARD A. BAKER, OF MANSFIELD, OHIO.

ROPE OR WIRE CLAMP.

1,238,167.

Specification of Letters Patent. Patented Aug. 28, 1917.

Application filed June 1, 1916. Serial No. 101,077.

To all whom it may concern:

Be it known that I, ROBERT D. MCINTYRE, a citizen of the United States, residing at Mansfield, in the county of Richland, State 5 of Ohio, have invented certain new and useful Improvements in Rope or Wire Clamps; and I do hereby declare the following to be a full, clear, and exact description of the invention, such as will enable others skilled 10 in the art to which it appertains to make and use the same.

This invention relates to rope, cable or wire clamps, and has for its primary object to provide a simple and efficient means for 15 firmly and securely gripping the cable, rope or wire so that the latter may be dragged, stretched or tightened.

A further object of the invention is to provide a device of this character wherein the 20 clamp more firmly binds upon the strand as the pull thereon is increased.

A still further object of the invention is to provide a device of this type further characterized by means for automatically maintaining 25 clamping surface or jaws yieldably in clamping engagement.

A still further and particular object of the invention is to provide a device of the character set forth which is of simple and inexpensive 30 construction, which is composed of but few readily assembled parts, all so arranged as to preclude breakage or derangement of the same, which is capable of application to cable, rope or wire of varied diameters or thicknesses, which is readily applied to or detached from the strand, and which will prove thoroughly efficient in the attainment of the ends for which it is designed.

With these objects in view, together with others which will appear as the description proceeds, the invention resides in the novel combination and arrangement of parts, all as will be described more fully hereinafter, 45 illustrated in the drawing, and particularly pointed out in the claims.

The invention will be best understood by reference to the accompanying drawings, wherein:

Figure 1 is a detail perspective view of the clamp member forming a part of the invention, the same being shown removed 50 from the base,

Fig. 2 is a similar view of the base,

Fig. 3 is a longitudinal section view taken 55 through the assembled device and showing the clamp member partially extended, and

Fig. 4 is a transverse sectional view taken on line 4-4 of Fig. 3.

In the preferred embodiment of the invention, a base 5 and slidable clamp member 6 are provided. The base is constructed of an elongated metallic bar, having depending from one end thereof a loop member 7 whereby the same may be readily gripped 60 with the fingers. The upper longitudinal edge of the base may be grooved and roughened as shown, the said portion being adapted for the reception of wire, rope or cable to be stretched. This base portion is cut 70 away upon one side to provide a right angular shoulder 8, the said shoulder being inclined from one end of the base downwardly toward the opposite end. A channel or groove 9 is bored in the base member 75 throughout the length of the latter beneath and in parallel relation to the shoulder 8. This bore or channel is preferably circular in cross-section, and communicates with the shoulder 8 at the juncture of the latter with 80 the upstanding portion of the base by the restricted slot 10.

The clamp or sliding member 6 is formed of an elongated metallic member equal in length and width to that of the base member 5. This clamping member is cut away for a portion of its thickness to provide a laterally projecting longitudinally disposed shoulder 11, the same being grooved longitudinally and roughened as shown, and is 90 adapted in operation to coöperate with the grooved upper edge of the base member in firmly binding the rope or wire to the device. The clamping member provides a central longitudinally disposed web 12, the latter 95 being of a thickness equal to the width of the restricted slot 10 of the base, and a rib 13 projects from the lowermost extremity of the web 12. This rib is circular in cross-section, being of a diameter substantially equal 100 to or a trifle less than that of the annular channel or groove 9 in the base portion. It will be observed that the rib 13 is disposed angularly throughout the length of the clamping member with relation to the 105 shoulder 11 thereof, the angularity of the

said rib being the same as that of the channel groove 9 of the base. The shoulder 14 projects laterally from the sliding member upon the side of the latter opposite to that 5 from which the shoulder 11 projects. The shoulder 14 extending throughout the length of the slidable member and is parallel with the web 12. The central portion of the rib 13 is cut away as shown, and an expansion 10 spring 15 is seated on one end against one of the end portions of the cut away rib, while the opposite end of the spring is looped as shown to engage around a pin or screw 16 extending laterally through the base member 15 and the channel thereof. Knob portions 17 may be provided at the ends of the slid- 20 able member 6 to facilitate sliding of the latter with the fingers.

The clamping member 6 is assembled upon 25 the base by inserting the rib 13 at the thick- est end thereof into the channel 9 at the nar- rowest extremity of the base portion 5. In- ward sliding movement of the clamping member will cause the rib to ride within the 30 groove 9 until limited in such inward move- ment by engagement of the clamping shoul- ders of the base and slid- able members. When in this position, the ends of the base and clamping member will be even. The 35 pin or screw 16 is then projected laterally through the base portion to engage the loop in the end of the expansion spring 15. When thus assembled, movement of the slid- able member rearwardly of the base or against 40 the tension of the spring 15, will cause the shoulder 11 carried by the clamping member to move outwardly away from the wire re- ceiving shoulder of the base. After the 45 strand has been inserted within the latter mentioned groove the slid- able member may be released, whereupon the spring 15 will force the clamping member 6 inwardly of the base and the shoulder 11 thereof will engage and firmly bind the strand within the groove 50 at the upper edge of the base portion. When a pull is delivered to the base member through the loop 7, the pressure will cause the slid- able member 6 to move inwardly of the base, whereupon a firm grip or clamping action 55 upon the strand throughout the length of the clamping shoulders will be created. It is thus seen that the greater pulling power delivered to the base will create a greater binding action upon the strand and yet this 60 action is attained without kinking or bend- ing the strand within the grip member. It is also apparent that the pin or screw 16 performs the two-fold function of support- ing the spring end, and limiting the inward 65 movement of the slid- able member upon the base.

While the above is a disclosure of the pre- 70 ferred embodiment of the invention, it is apparent that the same is susceptible of various changes in the minor details of con-

struction and arrangement of parts, and I reserve to myself the right to resort to such changes as I see fit without departing from the spirit of the invention or scope of the claims.

70

What is claimed is:

1. A device of the character described comprising a base member provided with a longitudinal channel, a clamping face angularly arranged with respect to said chan- 75 nel, a clamping member slidably mounted on said base, means carried by said clamping member for interengagement with the channel of said base for guiding the clamping member in its sliding movement, a clamping 80 face on the clamping member and arranged at an angle to the said guiding means, and means for retaining the clamping member and the base in interengagement.

2. A device of the character described 85 comprising a base provided with a longitu- dinal channel, a clamping face angularly ar- ranged with respect to said longitudinal channel, a clamping member, guiding means carried by the clamping member and adapt- 90 ed for interengagement with the channel in said base, a clamping face carried by the clamping member and arranged angularly with respect to said guiding means, and means for moving the clamping member 95 with respect to the base to maintain the clamping faces of each in juxtaposition.

3. A device of the character described comprising in combination, a base provided 100 with a longitudinal channel, a clamping face integral with the base and extending angularly with respect to said channel, a clamping member, a guide integral with the clamping member and adapted to be received within the channel of the base, a clamping 105 face carried by the clamping member, and resilient means for moving the clamping member longitudinally of the base to main- 110 tain the clamping face of the base and the clamping face of the clamping member in juxtaposition.

4. A device of the character described comprising a base member provided with a longitudinal channel, a clamping face angularly arranged with respect to said chan- 115 nel, a clamping member, a guide depending from the under face of the clamping member and adapted to be received within said chan- 120 nel, a clamping face integral with the clamping member and arranged angularly with respect to said guide member, a coil spring carried by the clamping member, and means passing through the base and engaging the coil spring to retain the clamping member and the base in interengaged relation.

5. A device of the character described 125 comprising a base member provided with a longitudinal channel, a clamping face in- 130 tegral with the base and angularly arranged with respect to said channel, a clamping

element, a guide carried by the clamping element and adapted to be received within the channel of the base member, a clamping face carried by the clamping element and 5 angularly arranged with respect to the guide thereof, and means for retaining the clamping element and base member in interengaged relation.

6. A device of the character described 10 comprising a base member provided with a longitudinal channel, a clamping face integral with the base member and angularly arranged with respect to said channel, a clamping element, a guide member integral 15 with the clamping element and adapted to be received within the channel of the base member to retain the clamping member and the base member in interengaged relation, a

clamping face integral with the clamping element and angularly arranged with respect to the guide member, resilient means 20 carried by the clamping element and lying within the channel of the base member to retain the clamping jaw of the clamping element and the clamping jaw of the base 25 member in juxtaposition, and means carried by the base member and engaging the resilient means carried by the clamping element to retain the base member and clamping element in interengaged relation. 30

In testimony whereof, I affix my signature, in the presence of two witnesses.

R. D. McINTYRE.
